FIG. 2.

UNITED STATES PATENT OFFICE.

BURNS ADAMS, OF SALT LICK, KENTUCKY.

IRONING BOARD.

Application filed August 15, 1928. Serial No. 299,813.

My invention relates to improvements in ironing boards of the foldable or collapsible type such as are commonly used in the home.

- 5 Briefly stated, the primary object of this invention is to provide a device of this character which will be of very simple and durable construction and which when set up for use will be most stable and rigid.
- 10 A further object of the invention is to furnish an ironing board, as characterized, which when folded up to be stored away will occupy a minimum amount of space.

15 A still further object of the invention resides in the provision of novel and improved supporting and locking means for preventing the device from collapsing while in use.

20 The invention also resides in certain novel features of construction, combination and arrangement of the various parts and in modes of operation which will be readily understood by those skilled in the art upon reference to the following descriptive matter in 25 connection with the accompanying drawings forming a part of this specification.

25 While the preferred embodiment of the invention has been illustrated in the drawings, yet it is to be understood that the same 30 is capable of considerable change and modification within the spirit and scope of the subject matter claimed hereinafter.

35 In the drawings, wherein the same reference characters have been used to designate the same parts in all views,

Figure 1 is a perspective view of the ironing board in folded position for storage;

Figure 2 is a perspective illustrating the ironing board set up for use;

40 Figure 3 is a detail sectional view of the prop and lock elements;

Figure 4 is a section on line 4—4 of Figure 1 and—

45 Figure 5 is a section on line 5—5 of Figure 1.

Referring specifically to the drawings,—numeral 1 designates the ironing board proper and this is shown as being screwed to the cross bar 2 adjacent its rear or wider end. The cross bar 2 is rotatably carried by the upper ends of the rear or upstanding legs 3. Suitable means, such as knobs 4, can be employed for rotatably connecting the cross piece 2 to the legs 3. Slightly below

the cross bar 2 and extending through the 55 legs 3 is a rung 5, which is tightly secured in legs 3 and receives the ends of forwardly extending legs 6. It is understood that the rung extends tightly into holes in the forwardly extending legs 6 and that the 60 rung 5 is rotatably carried by the rear legs 3.

Adjacent the lower ends of the legs 3 is a 65 second rung 7 and this likewise is tightly fitted into holes in the legs 3.

In order to maintain the relative position of the legs 3, 6, as shown in Figure 2, I employ a brace member 8, which is rotatably carried by the lower rung 7. The brace 8 comprises two sections 8^a, 8^b which 70 are suitably spaced by blocks 9, the entire assembly being screwed together tightly, as indicated at 10. Upon the rung 5 and between the sections 8^a, 8^b is a block 11. The block 11 is tightly fitted on the rung 7 so 75 as to hold the bearing end of the brace 8 exactly intermediate the ends of the rung 7 and between the rear legs 3.

The lower edge of the brace member 8 adjacent its outer end is provided with a notch 80 12, which is adapted to seat the rung 13, which is tightly fitted into the forwardly extending legs 6, intermediate the ends thereof. Thus, the brace member 8 serves to maintain the legs 3, 6 in a predetermined 85 relative position wherein the forward ends of the legs 6 will be disposed well toward the forward end of the ironing board.

Between the members 8^a, 8^b of the brace member 8 and located at the forward end of such brace member is the pivot pin 14 having journalled upon its intermediate portion the prop 15. Rearwardly of the pivot 14 the prop has its edge formed with a notch 16 adapted to embrace the rung 13 of forwardly 90 extending legs 6. Thus, by swinging the prop member 15 in a counterclockwise direction, as viewed in Figure 2, the notch 16 thereof will embrace the lower portion of the rung 13 so as to tightly clamp the brace 95 notch 12 thereupon. The under surface of the ironing board 1 adjacent the forward portion thereof is provided with a transverse cleat 17 having a bottom surface recess 18. In the set up position of the ironing board, 100 as shown in Figure 1, the upper end of the prop member 15 is adapted to engage the surface recess 18 of the cleat member 17 so 105

as to support the ironing board rigidly in position for use. Even if the upper end of the prop member 17 does not accurately engage in the recess 18 it will be manifest that 5 the ironing board will be firmly supported inasmuch as the prop member 15 is locked in engagement with the rung 13 of the forwardly extending legs 6. The angle at 10 which the prop member 15 is disposed is sufficiently forward or in advance of dead center as to prevent the prop member 15 from swinging in a clockwise direction to disengage from the rung 13 by engagement 15 of the ironing board with the upper end of such prop.

Adjacent the forward ends of the inclined legs 6 is a tie rung 20 having its ends tightly fitted into holes in such legs 6.

Referring to Figure 1 it will be noted that 20 the legs 3 fold inwardly so that their outer surfaces lie contiguous with the inner surfaces of the forwardly extending legs 6. Likewise the outer end of the prop member 15 has been folded inwardly so that its outer 25 portion lies in the space between the elements 8^a, 8^b of the brace member 8 with the notched end 16 directed toward the rear or wider end of the ironing board 1. The cross piece 2 has a central recess for receiving the free 30 end of brace 8. It is also to be noted that the cleat 17 of the ironing board is adapted to lie just outwardly of the intermediate rung 13 connecting legs 6.

Assuming that the ironing board is in 35 folded position, as shown in Figure 1, it may be readily opened for use by proceeding as follows:

First stand the folded ironing board on end with the smaller end of the board 1 40 extended toward the floor. Then pull the relatively long legs 6 outwardly until the board stands on the end with the legs out of contact with the ground. Then pull the legs 3 outwardly until the brace bar 8 will 45 come over to engage the intermediate rung 13, as shown in Figure 2. This having been done the prop member or lock post 15 should be pulled out in a counter clockwise direction, as viewed in Figure 2, until the notch 50 16 thereof engages the intermediate rung 13 of the leg 6. The ironing board 1 having been lowered to engage the upper end of the prop member 15 so that such ends will seat in the recess 18 of cleat 17,—the operation is 55 completed and the ironing board is ready for use.

Having thus described my invention, what I claim as new and desire to secure by Letters Patent is:

60 1. An ironing board comprising a table portion, relatively short legs pivotally connected to said ironing board and adapted to be normally disposed in upright position at the rear end of the board for supporting the same at such point, a second pair of legs 65 pivotally connected to said first mentioned legs adjacent the point of connection thereof with the ironing board, said second mentioned legs being long and adapted to extend diagonally downward and forward toward the front end of the board when in use, a rung connecting said last mentioned legs substantially intermediate the ends thereof, a rung connecting said first mentioned legs, a brace member carried by said last mentioned rung and having a notch in its lower edge adjacent its forward end, said notch being adapted to engage the intermediate rung of said second mentioned legs, a prop member pivoted to the forward end of said brace member in advance of said notch, said prop member having a notch opposed to the notch of said brace member 70

legs pivotally connected to said first mentioned legs adjacent the point of connection thereof with the ironing board, said second mentioned legs being relatively long and adapted to extend diagonally downward and forward toward the front end of the board when in use, a rung connecting said last mentioned legs substantially intermediate the ends thereof, a rung connecting said first mentioned legs, a brace member carried by said last mentioned rung and having a notch in its lower edge adjacent its forward end, said notch being adapted to engage the intermediate rung of said second mentioned legs, and a prop member pivoted to the forward end of said brace member in advance of said notch, said prop member having a notch opposed to the notch of said brace member 75 when the board is in operative position and adapted to engage the rung of said second mentioned legs at the side opposite the point of engagement by the notch of said brace member, and a cleat member carried by said ironing board at the under surface thereof, said cleat member having a recess adapted to receive the upper end of said prop member. 80

2. In a device of the class described comprising rear legs having an ironing board pivoted thereto and forwardly extended legs 95 pivoted to said rear legs, a brace and prop member comprising independent sections pivotally connected together, means pivotally connecting said brace member to said rear legs, a rung connecting said second mentioned legs, and said prop and brace members having co-acting locking portions adapted to embrace said rung from opposite sides thereof whereby to dispose said prop member in an upwardly extended position to support the ironing board. 100

3. An ironing board comprising a table portion, short legs pivotally connected to said ironing board and adapted to be normally disposed in upright position at the 110 rear end of the board for supporting the same at such point, a second pair of legs pivotally connected to said first mentioned legs adjacent the point of connection thereof with the ironing board, said second mentioned legs being long and adapted to extend diagonally downward and forward toward the front end of the board when in use, a rung connecting said last mentioned legs substantially intermediate the ends thereof, a rung connecting said first mentioned legs, a brace member carried by said last mentioned rung and having a notch in its lower edge adjacent its forward end, said notch being adapted to engage the intermediate rung of said second mentioned legs, a prop member pivoted to the forward end of said brace member in advance of said notch, said prop member having a notch opposed to the notch of said brace member 115 120 125 130

when the board is in operative position and adapted to engage the rung of said second mentioned legs at the side opposite the point of engagement by the notch of said brace 5 member, and said prop when its notch is engaged with said intermediate rung being disposed in an upward and forwardly ex-

tending position to support the table portion whereby the weight of the latter holds the prop against movement to disengage its 10 notch from said intermediate rung.

In testimony whereof I affix my signature.

BURNS ADAMS.
